US0D1002607S

(12) **United States Design Patent** (10) **Patent No.:** **US D1,002,607 S**
(45) **Date of Patent:** **** Oct. 24, 2023**

(54) **ELECTRONIC DEVICE**

(71) **Applicant:** **Apple Inc.**, Cupertino, CA (US)

(72) **Inventors:** **Jody Akana**, Los Altos Hills, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Clement Tissandier**, San Francisco, CA (US); **Eugene Antony Whang**, San Francisco, CA (US); **Rico Zörkendörfer**, San Francisco, CA (US)

(73) **Assignee:** **Apple Inc.**, Cupertino, CA (US)

(**) **Term:** **15 Years**

(21) **Appl. No.:** **29/853,785**

(22) **Filed:** **Sep. 19, 2022**

Related U.S. Application Data

(63) Continuation of application No. 29/682,056, filed on Mar. 1, 2019, now Pat. No. Des. 964,350, which is a continuation of application No. 29/626,614, filed on Nov. 17, 2017, now Pat. No. Des. 842,298, which is

a continuation of application No. 29/557,263, filed on Mar. 7, 2016, now Pat. No. Des. 803,209.

(57) **CLAIM**

The ornamental design for an electronic device, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front perspective view of an electronic device showing the claimed design;

FIG. 2 is a rear perspective view thereof;

FIG. 3 is a front view thereof;

FIG. 4 is a rear view thereof;

FIG. 5 is a top view thereof;

FIG. 6 is a right side view thereof;

FIG. 7 is a left side perspective view thereof; and,

FIG. 8 is a bottom perspective view thereof.

The dot-dash broken lines in the figures and the area(s) within the dot-dash broken lines show portions of the electronic device that form no part of the claimed design.
